COMBINED STORAGE CABINET AND DISPLAY RACK FOR CLOTHES

Maurice Cohen, 3580 NW. 52nd St., Miami, Fla.

Filed Oct. 8, 1962, Ser. No. 72,027

Term of patent 14 years

(Cl. D80—11)

FIG. 2

FIG. 1 is a front perspective view taken from one side of a combined storage cabinet and display rack for clothes, showing my new design, the opposite side and rear being substantially the same as the side and front shown, respectively; and

FIG. 2 is a top plan view thereof.

I claim:

The ornamental design for a combined storage cabinet and display rack for clothes, as shown and described.
